UNITED STATES PATENT OFFICE.

KARL SCHMIDT, OF HAMBURG, GERMANY.

SIGNALING APPARATUS FOR WAITERS.

Application filed November 25, 1925, Serial No. 71,424, and in Germany December 1, 1924.

The usual signaling-arrangements, by which the guest indicates through sound- or light-signals, that he wishes the waiter to come to him have the disadvantages of a very complicated construction, and the costs of manufacturing are much too high, also they are unreliable when in use, for that reason very few of these arrangements have been bought up to now.

10 The object of the invention is a signaling-arrangement for waiters, which has against all known similar arrangements the advantages of an exceedingly simple construction, the costs of manufacturing are very small, it will always remain in good working-condition, and because they can be delivered free of charge to owners of restaurants, coffee-houses and so on, they can be used for advertising-purposes, so that it is possible 15 to distribute this arrangement very quickly and this will do away with the long waiting for the waiter.

The arrangement is constructed in the following manner:

20 Upon an ash-tray or any other object used in restaurants or the like localities two posts are fixed, which have between their top-ends either upon an axle or between plugs a rotary disk, which is provided with directions for use of the arrangement. The disk is 25 usually in an upright position, but when the guest requires the service of the waiter the disk is turned in a horizontal position, so that the waiter may know that he is 30 wanted by the guest. As soon as the guest has given his order to the waiter, the disk is again placed in the upright position.

In the accompanying drawings
Figure 1 is a front elevation of my im-
proved signaling apparatus.

Figure 2 is a detail sectional view of the same.

Upon a socle α , which by way of example is formed like an ash-tray, two posts b and c are fastened. Between the top-ends of the posts b and c is placed either upon an axle

or between plugs e and f a rotary disk or plate d . The disk d is provided with directions for use of the arrangement and is held in its upright position by an elastic bolt g 50 which projects inwardly from the post b and is arranged at its projecting end to engage one side edge of the disk and hold the latter in fixed position when desired. When the disk has been turned into horizontal position 55 it is held in such position by the plugs e and f or other suitable means. For instance, either or both of the plugs e and f may be provided with a block e' arranged therewith, and having a flat side and a spring h 60 may be provided to bear against the edge of said block and so arranged as to engage the flat side when the disk d is horizontal and thus by friction hold the disk in horizontal position. Any suitable means such as is well 65 known to skilled mechanics may be employed for this purpose.

The outer surface of the socle α can be used for advertising-purposes. The posts b and c are made in such a way, so as to allow 70 the placing of one or more exchangeable plates between the socle α and the disk d ; both sides of these plates can also be used for advertising-purposes.

I claim:—
A waiter signal comprising a base, posts rising from the base and a disc pivotally mounted between the upper ends of the posts, the pivotal axis of said disc being horizontal and substantially midway between the sides of the disc and the width of the disc and the height of the posts being such that when the disc is in vertical position space is provided between the posts and between the base and the disc for the placing of advertising devices and an elastic bolt projecting inwardly from one of the posts and arranged at its projecting end to engage one side edge of the disc and hold the latter in fixed position when desired. 80

In testimony whereof I affix my signature.
KARL SCHMIDT.
